INTAGLIO PRINTING MACHINE

Filed July 20, 1929

Inventor:

Amato Egli

UNITED STATES PATENT OFFICE

ARNOLD EGLI, OF HAMBURG, GERMANY

INTAGLIO PRINTING MACHINE

Application filed July 20, 1928, Serial No. 294,272, and in Germany July 28, 1927.

It is generally necessary in intaglio-printing-machines, especially for intaglio-sheet-printing-machines, for the printing- and impression-cylinders to be separated very quickly by a distance of about $\frac{3}{2}$ in. in order to allow the passing of a sheet or portion of a web without its being touched by the printing-cylinder or printed by it.

It is known how to shift the printing-cylinder in the direction of pressure of the locally fixed scraper towards the impression-cylinder and away from it, in such a way that a decrease or increase is produced of the pressure exerted upon the printing cylinder by the scraper. In fine printing, however, the change in pressure of the scraper will be visible in the difference of tinge of the sheets being printed and is therefore very objectionable.

This undesirable effect is less noticeable in single colour-printing-machines, as an interruption of the printing-process occurs very seldom, but it would be practically impossible to produce a multiple-colour-intaglio-printing of good quality because of this effect, since after every printing-operation of the machine one or more stops are necessary.

Besides the foregoing other intaglio-printing-machines are known, where the printing-cylinder with the scraper belonging to it can be shifted in radially arranged wings towards the impression-cylinder and away from it. The purpose of this device is to interrupt the printing upon an endless paper-band, to which the colours are transferred from the rubber impression-cylinder by means of several colour-inking rollers similar to offset-printing in order to terminate the work of the machine.

The problem however of producing a multiple-coloured intaglio-printing cannot be solved by means of such a device, as intaglio-printing is a printing process which, because of its peculiar character, requires absolute accuracy. If, for the purpose of guiding the printing-cylinders, wings are arranged in the well known manner, the guiding of the stone-blocks in the wings supporting the printing-cylinders must work so

easily, that the required velocity of the shifting-movement is actually attained; such guiding can however, be effected only by a relatively large play between the stone-blocks and the wing-guides. This great play causes great inconveniences in intaglio-printing on account of its fineness, as a completely obliterated print is produced. If now instead of loosely guiding the moving mechanism, strong forces are applied not only are knocks produced but, on account of the strong friction of the parts working against each other this play and therewith the before mentioned disadvantages again appear.

The invention about to be described does away with these disadvantages by providing a novel mounting for the printing-cylinder, which moves towards and away from the impression-cylinder, such printing-cylinder according to the invention being journaled in supporting plates which are swingable about a rotary pivot, the latter being in substantially vertical alignment with the center of the cylinder. Because of the small friction areas at the pivot of the supporting-plates only small forces need be exerted for oscillating the printing-cylinder in spite of the fact that the pivots are mounted in the bearings without play. When each pivot is arranged in a vertical line passing through the center of gravity of the associated printing-cylinder-system, the latter can be moved through comparatively large angular displacements without raising or lowering such center of gravity to any considerable extent, in consequent of which practically no more power is needed for oscillating the printing-cylinder toward and away from the impression-cylinder than is necessary to overcome the friction at the rotary-pivot-bearing. If the pivot of the plates in the vertical line through the center of gravity of a printing-cylinder-system is arranged below the center of gravity the system being then in unstable equilibrium as it is balanced upon the pivot shaft, a further advantage is obtained in that when the printing-cylinder-system is swung out of its position of unstable equilibrium only part of the distance to the impression cylinder, the weight of the printing-cylinder-system itself

acts to move the system for the rest of such distance in consequence of which less power for the shifting action is required.

A further advantage flowing from the use 5 of pivoted supporting plates mounted on rotary pivots in accordance with my invention lies in the fact that the scraper as well as the inking-roller can be arranged on such plates, in consequence of which the scraper and the 10 inking-roller are oscillated together with the printing cylinder, thereby preventing any change in their relative positions. The printing cylinder is thus engaged with a constant and uniform pressure by the scraper, regardless 15 of whether it is in the printing position or has been moved away from the impression cylinder. The inking-roller is likewise kept at a uniform distance from the printing cylinder, so that the inking action is not influenced 20 in any way.

A preferred form of the invention is illustrated diagrammatically by way of example in the accompanying drawing. As shown on such drawing, a rotary pivot (c) is arranged 25 substantially vertically below the shaft (a) of the printing-cylinder (b). Upon this rotary pivot (c) supporting-plates (d) are journalled to swing-out and receive the shaft (a) of the printing-cylinder (b), the bearings (e) 30 of the scraper-holder (f) and the adjustable bearings (g) of the inking-roller (h).

Because of the fact that the pivot (c) is arranged perpendicularly below the shaft (a) of the printing cylinder (b), the center of 35 gravity of which, in consequence of the preponderating weight of the printing cylinder, has nearly the same position as the center of gravity of the printing cylinder, scraper and inking-roller system, the entire load of the 40 system is supported by the pivot, so that to move or oscillate the plates and the mechanism supported thereby only the friction of the pivot (c) must be overcome. Immediately 45 after the movement of the printing cylinder, scraper, and inking-roller system out of the position of unstable equilibrium has started, the weight of the system acts to overcome a part of the friction forces existing on 50 the circumference of the rotary pivot (c) and as a result the pivot (c) engaged by the known elements for shifting the position of the supporting plates, need exert for the shifting action only a fraction of the friction forces.

55 I claim:

1. In an intaglio printing machine, in combination, an impression cylinder, a pair of carrier frames pivoted adjacent to said cylinder, a printing cylinder journalled in said carrier frames, and means for oscillating said frames on their pivots to move the printing cylinder alternately toward and away from the impression cylinder, the pivotal axis of 60 said plates being in substantial vertical alignment with the center of gravity of the mass 65

mounted on said pivots, whereby oscillation of the printing cylinder toward and away from the impression cylinder is effected without appreciably raising or lowering said center of gravity, and the power required to move 70 said printing cylinder is reduced.

2. In an intaglio printing machine, in combination, an impression cylinder, a pair of carrier frames pivoted adjacent to said cylinder, a printing cylinder journalled in said carrier frames, and means for oscillating said frames on their pivots to move the printing cylinder alternately toward and away from the impression cylinder, the pivotal axis of 75 said plates being in substantial vertical alignment with and located below the center of gravity of said printing cylinder, whereby oscillation of the printing cylinder toward and away from the impression cylinder is effected without appreciably raising or lowering 80 said center of gravity, and the power required to move said printing cylinder is reduced.

3. In an intaglio printing machine, in combination, an impression cylinder, a pair of carrier frames pivoted adjacent to said cylinder, a printing cylinder journalled in said carrier frames, an inking roller and a scraper likewise mounted on said frames, and means for oscillating said frames on their pivots to move the printing cylinder alternately toward and away from the impression cylinder, the pivotal axis of 90 said plates being in substantial vertical alignment with and located below the center of gravity of the printing cylinder, inking roller and scraper, whereby oscillation of the printing cylinder toward and away from the impression cylinder is effected without appreciably raising or lowering 95 said center of gravity, and the power required to move said printing cylinder is reduced.

In testimony whereof I have hereunto set my hand.
